UNITED STATES PATENT OFFICE

CLARENCE LILE, OF GRANITE CITY, ILLINOIS

DESIGN FOR A BOTTLE-CAP REMOVER

Application filed November 20, 1930. Serial No. 37,732. Term of patent 14 years.

To all whom it may concern:

Be it known that I, CLARENCE LILE, a citizen of the United States, residing at Granite City, county of Madison, State of Illinois, have invented a new, original, and ornamental Design for Bottle-Cap Removers, of which the following is a specification, reference being had to the accompanying drawing, forming a part hereof.

In the drawings Fig. 1 is a front elevation of the cap remover showing my new design; Fig. 2 is a side elevation thereof.

I claim:

The ornamental design for a bottle cap remover, as shown.

CLARENCE LILE.
